JOHN ROUSE AND CHARLES ROUSE, OF TAFT, AND MAX ROUSE, OF LOS ANGELES, CALIFORNIA.

SPRING AND MATTRESS DISPLAY RACK.

Application filed February 17, 1926. Serial No. 88,787.

This invention relates to a device adapted to facilitate the storing and displaying of springs and mattresses.

As far as we are aware, there has hitherto been no apparatus or device which was adapted to support a plurality of springs and mattresses in a position where these springs and mattresses could be readily observed and from which they could be separately drawn out for better display.

It is the object of the present invention to provide a display rack by which a plurality of springs supporting mattresses can be maintained, one above the other in horizontal positions, where the character of the springs and mattresses can readily be seen and where each spring and mattress may be separately and easily drawn out into more complete view.

Various further objects and advantages of the present invention will appear from a description of a preferred form of spring and mattress display rack embodying the invention. Accordingly, we have shown in the accompanying drawings, a preferred example of a display rack embodying the present invention.

In the drawings:

Figure 1 is a front elevation,
Figure 2 is a side elevation,

Figure 3 is an enlargement of the traveling supporting bar and its mounting,

Figure 4 is another view of said bar,

Figure 5 is a perspective view of the traveling supporting bar and a horizontal bracing of the rack which also serves to slidably mount said traveling bar,

Figure 6 is a fragmentary view of a modified form of roller to be employed in the apparatus,

Figure 7 is a fragmentary perspective view illustrating a modified form of holder for engaging the springs, and

Figure 8 is a further modified form of holder for engaging the springs.

Referring to the drawings, the rack is illustrated as comprising a skeleton frame adapted to permit a view of the several mattresses and springs supported thereby, while said mattresses and springs are slid back within the frame, the frame comprising the vertical member or irons 2 at the corner and the lower set of horizontal members or irons 3 at the bottom of the frame and an upper set of horizontal members or irons at

the top of the frame 4. Each corner of the skeleton frame is provided with a triangular bracing plate 5, pivoted to the adjacent members or irons of the frame.

To the sides of the frame are secured further horizontal members or angle irons 6 which are vertically spaced apart and serve both as horizontal braces and as supports for sliding supports or bars 7. In the particular rack illustrated, there are three of the horizontal members or angle irons 6 at each end of the frame, arranged opposite each other, to provide for the support of three sets of springs and mattresses, as illustrated in Figure 1. These angle irons 6 each support a plurality of spaced apart arms 8, the ends of which mount rollers 9 for the traveling members or supporting bars 7. The bars or supporting members 7 in turn are preferably of hollow form so that the rollers 9 may fit within the bars 7 and thus prevent any movement of the bars 7 except in a direction longitudinal to the bars. The hollow bars or supporting bars 7 having a longitudinal opening in their outer socket through which the arms 8 supporting the rollers 9 may extend. The ends of these sliding supporting members or bars 7 are provided with suitable means, such as the upstanding pins 11, for preventing a spring mounted on the bars from sliding off the same, there being indicated pins at each end of the bars 7 and pins at the outer side of each bar 7 so that a spring when mounted thereon is held from sliding relative to the supporting or traveling bar 7.

There is also provided a suitable means to limit the outward motion of the supporting bars 7, such, for example, as stops 12, supported by the horizontal irons 6. With the above described rack, a spring supporting a mattress may be rested upon each part of the supporting bars 7 so that the rack accommodates three sets of springs and mattresses, the rack being of skeleton form. The mattresses and springs are then already partly displayed, and whenever desired to more particularly display any of the thus supported springs and mattresses, by engaging any part of the mattress or of the spring, it may be drawn out partially from the rack through the supporting bars 7 sliding or rolling on the rollers 9.

Referring now to Figure 6, the supports for the traveling members or supporting

bars 7, are shown in modified construction, in which the arms 8^a supported at the angle irons 6, each carry rollers 9^a mounted upon roller bearings 13. The ends of the arms 8^a extend beyond the rollers 9^a and they are bifurcated, as indicated at 14. The bifurcations support a transverse pin 15 on which is mounted a roller 16 adapted to engage the inner side wall of the track 7^a. This form of support for the traveling bars or tracks 7^a is found to substantially facilitate the withdrawal of the springs and mattresses due to the action of the end rollers 16 on the arms 8^a, preventing the traveling members 7^a from binding against the arms 8^a.

Referring to Figures 7 and 8, the holders or stops which engage the springs on the traveling bars 7 are shown as a somewhat modified form in which the holder 17 is shown as provided with a flat base portion 18, bolted to the bar 7, and provided with an upstanding circular portion 19 for fitting against the rounded corners of a spring supported in the rack. This form of the invention is particularly adapted to holding springs in which the corners are rounded.

In Figure 8, there is a further modified form of holder 20 having a flat horizontal portion 21 bolted to the bars 7 and a straight upstanding portion 22 for engaging the ends or sides of a spring supported thereon. Different forms of springs may require the use of different forms of holding members and the invention includes various different forms of such members.

While the particular display rack herein described is found to be of great value in facilitating the display of mattresses and springs, it is understood that various modifications in the rack may be made without departing from the invention. The invention is of the scope set forth in the appended claims.

What we claim is:

1. In a device of the class described, a frame, a plurality of sets of supporting bars slidably mounted by the frame one above the other, said bars being arranged in horizontally aligned pairs, the individual members of which are independently movable, the bars further being provided with means for engaging a spring resting upon a pair

of the horizontally aligned bars, whereby said bars will be caused to move in unison with movement of the spring.

2. In a rack for supporting the spring and mattress, the combination of a skeleton frame, a plurality of sets of mounting arms supported by the frame, rollers mounted upon the arms, hollow supporting bars fitted over the rollers, said bars being independently slidable on said rollers, and means on said bars adapted for engagement with a spring supported on two of said bars to cause said bars to operate in unison with the movement of the supported spring.

3. In a rack for supporting a spring and mattress, the combination of a skeleton frame, a plurality of vertically spaced apart horizontal members at opposed sides of the frame, arms secured to said bars extending inwardly and provided with rollers at their ends, and hollow supporting bars mounted upon said rollers with the rollers within the bars, said bars being independently movable, and means on said bars for preventing a spring set thereon from sliding relative to said bars, said means being adapted also when the spring is set on a pair of said bars to cause the two supporting bars to move in unison.

4. In a rack for supporting a mattress mounted upon a spring, the combination of a skeleton frame, a plurality of vertically spaced apart horizontal members at opposed sides of the frame, arms secured to said members extending inwardly and provided with rollers to turn in a direction transverse to the bars and also supporting rollers at their ends to revolve in horizontal planes, and hollow supporting bars mounted upon said rollers with the rollers within the bars, said bars being independently movable on said rollers, and means on said bars for engaging the bottom of a spring set thereon for holding the spring from sliding relative to said bars, said means being adapted when the spring is set upon two of said bars for causing the bars to move in unison with the spring.

Signed at Taft, California, this 9th day of February, 1926.

JOHN ROUSE.
